Primary Examiner — Kimberly Barnes

(57) **CLAIM**

The ornamental design for a water flotation suit, as shown and described herein.

DESCRIPTION

FIG. 1 is top, front, left side perspective view of an embodiment of a water flotation suit embodying a novel design; FIG. 2 is a front elevation view of the embodiment of FIG. 1;

FIG. 3 is a rear elevation view of the embodiment of FIG. 1;

FIG. 4 is a left side elevation view of the embodiment of FIG. 1;

FIG. 5 is a right side elevation view of the embodiment of FIG. 1;

FIG. 6 is a top plan view of the embodiment of FIG. 1; and FIG. 7 is a bottom plan view of the embodiment of FIG. 1; FIG. 8 is top, front, left side perspective view of another embodiment of a water flotation suit embodying a novel design;

FIG. 9 is a front elevation view of the embodiment of FIG. 8;

FIG. 10 is a rear elevation view of the embodiment of FIG. 8;

FIG. 11 is a left side elevation view of the embodiment of FIG. 8;

FIG. 12 is a right side elevation view of the embodiment of FIG. 8;

FIG. 13 is a top plan view of the embodiment of FIG. 8; and, FIG. 14 is a bottom plan view of the embodiment of FIG. 8. The broken lines shown are included for the purpose of illustrating portions of the water flotation suit that form no part of the claimed design.

1 Claim, 10 Drawing Sheets

Related U.S. Application Data

which is a continuation-in-part of application No. 29/582,642, filed on Oct. 28, 2016, now Pat. No. Des. 840,130.
